UNITED STATES PATENT OFFICE

2,150,613

CONTINUOUS HEATING FURNACE

Theodor Stassinet, Dinslaken, Germany

Application July 26, 1937, Serial No. 155,760
In Germany August 11, 1936

9 Claims. (CL. 263—6)

This invention relates to continuous heating furnaces which may be of the pusher type having a metal charging and a metal discharging opening at opposite ends of the furnace.

5 It is an object of the invention to obtain more favorable conditions in the soaking chamber of the furnace. In furnaces of the kind described for instance in Patent 1,912,933, it is old to provide a vertically restricted passage connecting the abutting ends of the heating and soaking chambers but this passage by itself is not able to maintain superatmospheric pressure in the soaking chamber which is required for satisfactory operation, as will be explained.

10 With the object of the invention in mind, means for imparting whirling motion to the gas flowing through the passage are provided on the transverse wall, or on the bottom or on the side walls of the furnace defining the restricted passage, or on any one of the defining members. Such means may be ribs defined by grooves in any, or all, of the members, or projections from the inner surface of any, or all, of the members. The whirls increase the resistance to the flow of 15 gas and by these the required pressure in the soaking chamber is obtained with a lesser volume of gas.

20 Several embodiments of the invention are illustrated, by way of example more or less diagrammatically in the accompanying drawing in which:—

25 Fig. 1 is a longitudinal section of a furnace in which the means for imparting whirling motion to the gas is on the transverse wall forming the restricted passage.

30 Figs. 2, 3, 4 and 5 are longitudinal sections of the passage illustrating various modifications of the said means.

35 Fig. 6 is a section similar to the sections in Figs. 2 to 5 but showing a structure for raising and lowering individual components of the means.

40 Fig. 7 is a cross-section of the restricted passage showing a structure for raising and lowering the transverse wall itself.

45 Fig. 8 is a cross-section showing means for imparting whirling motion arranged in the sole and in the side walls of the restricted passage.

50 Referring now to the drawing, and first to Fig. 1, the furnace 10 has a roof 2 for the pre-heating chamber *c* and the heating chamber *b*, a transverse wall 1 forming the restricted passage *d*, a roof 14 for the soaking chamber *a*, a knuckle 16, and the usual burners 15. The metal being 55 heated, here shown as billets 11, is introduced

through the charging opening 12 and leaves the soaking chamber *a* in annealed condition through the discharging opening 13.

The transverse wall 1, Fig. 2, has three transverse grooves 4 between ribs 3 in its lower surface for the purpose specified. 5

It is preferred to subdivide the hearth of continuous pusher furnaces into several sections such as *c*, *b*, *d* and *a* each of which has its own object. For instance, a continuous heating furnace showing this subdivision is described in the patent to Culbertson, No. 1,912,933. The subdivision of the hearth is indicated by the configuration of the roofs for the several sections, as 10 2, 1, and 14 in Fig. 1. 15

The metal billets 11 are heated to the highest temperature in the heating chamber *b*. It is not enough that the amount of heat required be absorbed by the metal but it is necessary that the temperature should be uniform throughout 20 the metal. However, it is very difficult to obtain uniform distribution of temperature under the intense heating action of the heating chamber *b*, and therefore the soaking chamber *a* is provided and heated by its burner 15 only to such 25 an extent as to make up for the loss of heat by transfer to the side walls, the roof and the sole of the soaking chamber, and to the gas flowing to the discharge opening 13, but the metal must not be heated to higher temperature in the 30 soaking chamber.

The make-up heat supplied to the soaking chamber is comparatively small and with furnaces having a plain transverse wall 1, is not sufficient for maintaining superatmospheric 35 pressure in the soaking chamber, or for filling the soaking chamber completely with furnace gas. The loss through cold air is particularly bad in furnaces in which the charging opening 12 and the discharging opening 13 are arranged at 40 opposite ends of the furnace, as shown. Here, the air is drawn into the soaking chamber *a* through the discharging opening 13 if the pressure in the chamber falls to below atmospheric, causing considerable scaling of the metal. This 45 must be avoided under all conditions.

Heretofore the only remedy available was to introduce large volumes of furnace or neutral gas but this is by no means satisfactory for the large volume of such gas, or gases, cause over-heating of the metal, delay or even prevent uniform distribution of temperature in the metal and involve undesirable extra cost. These drawbacks are particularly grave during shut-down periods. 50 55

To overcome these drawbacks, it was attempted to reduce to the minimum the clearance between the transverse wall and the plane of travel of the metal but there is a limit to this since the transverse wall must be positioned so as to permit the maximum thickness of metal to pass freely below it, with consideration of the fact that the billets may rise one upon the other and damage the transverse wall if it is arranged at 10 too low a level.

The resistance of restricted passages as provided heretofore was too low under all conditions, even if the transverse wall was lowered to the extent practicable and so it was necessary to supply to the soaking chamber two or three times the volume of combustion and/or neutral gas required for making up for heat loss.

According to the invention, therefore, the old expedient of whirling is resorted to by providing the means described for imparting whirling motion to the gas as it flows through the restricted passage *d*. Such means may be arranged in the transverse wall 1 in the shape of the transverse grooves 4 hereinabove described, or similar grooves may also be provided in the side walls 25 and/or the sole of the furnace where the restricted passage *d* is situated.

A transverse wall of this type is simple in design and the resistance it produces is easily calculated. The unobstructed cross-section of the passage, or the clearance between the lowest point of the transverse wall 1 and the furnace sole, is made equal to that provided in the existing furnace.

Whirls or eddies are produced by the transverse grooves 4 which increase the resistance to the flow of gas in the restricted passage *d* and the same pressure in the soaking chamber *a* is produced with a smaller volume of furnace and/or neutral gas.

Generally the resistance increases with the number of grooves provided but there should not be too many grooves since it has been found that the resistance decreases if a certain limit number of grooves is overstepped. It has been found, that the efficiency of the restricted passage according to the invention is a maximum if the Reynolds' number is 1800 to 5000, and preferably about 2200.

With three grooves 4, as shown in Figs. 1 and 2, the volume of gas required for obtaining the same pressure in the soaking chamber *a* is only one-half of that required in the existing furnaces, and this volume in many cases is just that required as make-up for heat loss. The heating of the soaking chamber is independent of the furnace operation and the same volume of gas is consumed in the soaking chamber during shut-up periods and periods of increased output, and the metal is not overheated. Heretofore during long shut-down periods the supply of gas to the soaking chamber had to be throttled to prevent overheating but if this is done cold air immediately penetrates into the soaking chamber and causes scaling of the metal. This drawback is eliminated according to the invention.

A very simple construction of the transverse wall is obtained by making the bricks 3 which form the ribs deeper than the bricks 4' defining the grooves, as shown for three grooves 4 in Fig. 2, and for two grooves 4 in Fig. 3.

For increasing the resistance recesses 5 may be formed in the walls of the bricks 3 defining the grooves 4 as shown in Fig. 4, and such recesses may be formed in the rear walls only, as

shown in full lines, or in the front walls also, as shown in dotted lines.

Fig. 5 shows bricks 3' of angular cross-section as defining the grooves 4. The longer shanks of these bricks project below the lower surface of 5 the transverse wall.

A somewhat less efficient structure of the transverse wall is obtained by making the bricks in each transverse and in each longitudinal row of the transverse wall 1 of different depths while 10 bricks in two distinct rows whose corners are in contact with each other, are of equal depth. By such means an arrangement like a chess board is obtained in which the dark areas correspond to bricks of lesser depth. The adjacent bricks in 15 the transverse rows may be of equal size, or of different sizes. The resistance is, perhaps, not as high as that of grooves and ribs but on the other hand the transverse wall will stand shocks from the metal or from furnace implements better 20 than a grooved wall.

The resistance is regulated within certain limits by providing means for raising and lowering the bricks 4' at the bottom of each groove, as shown in Fig. 6. The bricks 4' are suspended 25 from a bracket 17 at the lower end of a steel structure 18, and similar means may be provided for raising and lowering the transverse wall 1 itself, as shown in Fig. 7. A beam 8, of I-section, is connected to the structure 18 at its top and 30 supported by nuts 9 on a pair of threaded rods 6 secured to the steel plates 19 of the furnace at their lower ends.

Instead of raising and lowering the transverse wall 1 as a unit, it is possible to suspend any, or 35 all, of the bricks from a structure as described in order to adapt the clearance of the restricted passage *d* to metal of various thickness, and to attain the minimum gas consumption of the soaking chamber *a* even with the most difficult shapes 40 of metal parts.

If desired, grooves 21 may be made in the side walls 20 of the furnace, at the restricted passage *d* as shown in Fig. 8, and, if the metal is heated from below in the soaking chamber *a*, the sole 45 may also be grooved as indicated at 22. Obviously such grooves 21 and/or 22 may be combined with a grooved transverse wall 1.

Obviously the invention can be adapted to pusher furnaces in which a welding hearth is 50 provided instead of the soaking chamber *a*.

In all embodiments of the invention superatmospheric pressure is maintained in the soaking chamber *a* even at its lowest point, with a minimum volume of furnace and/or neutral gas.

I claim:—

1. A continuous heating furnace, comprising, a heating chamber having a metal charging opening, a soaking chamber having a metal discharging opening, a transverse wall extending 6 downwardly towards the plane of travel of the metal being heated to form a vertically restricted passage connecting the abutting ends of the heating and soaking chambers, a bottom, and side walls defining the restricted passage, and ribs 6 on the inner surface of one of the said defining members for imparting whirling motion to gas flowing through the passage, and independent heating means for the heating and soaking chambers.

2. A continuous heating furnace, comprising a heating chamber having a metal charging opening, a soaking chamber having a metal discharging opening, a transverse wall extending 7 downwardly towards the plane of travel of the

5 metal being heated to form a vertically restricted passage connecting the abutting ends of the heating and soaking chambers, and the face of the transverse wall having grooves for imparting whirling motion to gas flowing through the passage, and independent heating means for the heating and soaking chambers.

10 3. A continuous heating furnace, comprising a heating chamber having a metal charging opening, a soaking chamber having a metal discharging opening, a transverse wall having recessed portions extending downwardly towards the plane of travel of the metal being heated to form a vertically restricted passage connecting the abutting ends of the heating and soaking chambers to impart a whirling motion to gases flowing through the passage, and independent heating means for said chambers.

15 4. A continuous heating furnace, comprising a heating chamber having a metal charging opening, a soaking chamber having a metal discharging opening, a transverse wall having recessed portions arranged transversely of the furnace and extending downwardly towards the plane of travel of the metal being heated to form a vertically restricted passage connecting the abutting ends of the heating and soaking chambers to impart a whirling motion to the gases flowing through the passage, and independent heating means for said chambers.

20 5. A continuous heating furnace, comprising a heating chamber having a metal charging opening, a soaking chamber having a metal discharging opening, a transverse wall extending downwardly towards the plane of travel of the metal being heated to form a vertically restricted passage connecting the abutting ends of the heating and soaking chambers, bricks of greater depth alternating with bricks of lesser depth on the lower surface of the wall to impart a whirling motion to gases flowing through the passage, and independent heating means for said chambers.

25 6. A continuous heating furnace, comprising a heating chamber having a metal charging opening, a soaking chamber having a metal discharging opening, a transverse wall extending downwardly towards the plane of travel of the metal

being heated to form a vertically restricted passage connecting the abutting ends of the heating and soaking chambers, and angular bricks projecting from the lower surface of the wall with one of their angle portions extending transverse to the flow of gases between the chambers to impart a whirling motion to the gases flowing through the passage, and independent heating means for said chambers.

30 7. A continuous heating furnace, comprising a heating chamber having a metal charging opening, a soaking chamber having a metal discharging opening, a transverse wall extending downwardly towards the plane of travel of the metal being heated to form a vertically restricted passage connecting the abutting ends of the heating and soaking chambers, bricks of greater depth alternating with bricks of lesser depth on the lower surface of the wall to impart a whirling motion to gases flowing through the passage, and independent heating means for said chambers.

35 8. A continuous heating furnace comprising a heating chamber having a metal charging opening, a soaking chamber having a metal discharging opening, a transverse wall extending downwardly towards the plane of travel of the metal being heated to form a vertically restricted passage connecting the abutting ends of the heating and soaking chambers, bricks of greater depth alternating with bricks of lesser depth on the lower surface of the wall to impart a whirling motion to gases flowing through the passage, means for raising and lowering the bricks which are of lesser depth, and independent heating means for said chambers.

40 9. A continuous heating furnace, comprising a heating chamber having a metal charging opening, a soaking chamber having a metal discharging opening, a transverse wall extending downwardly towards the plane of travel of the metal being heated to form a vertically restricted passage connecting the abutting ends of the heating and soaking chambers, means on the lower face of the transverse wall for imparting whirling motion to gas flowing through the passage, means for raising and lowering the transverse wall, and independent heating means for said chambers.

45 THEODOR STASSINET.
